UNITED STATES PATENT OFFICE

ALBIN W. GRONQUIST, OF BRAINERD, MINNESOTA, ASSIGNEE OF ONE-HALF TO ISAAC GINSBURG, OF BRAINERD, MINNESOTA

WHISTLE

Application filed November 24, 1930. Serial No. 437,672.

This invention relates to whistles, particularly, although not exclusively, adapted for use in the air lines of railway trains.

It is my object to provide an inexpensive and unusually strong and durable whistle of this kind whereby the original cost and expenses of up-keep and installation are reduced.

The invention will be best understood by reference to the accompanying drawings in which Figure 1 is a side elevation of my improved whistle, partially in central vertical section; Fig. 2 is a central longitudinal section through the same taken at right angles to the section portion shown in Fig. 1 and Fig. 3 is a detail plan view of the head for connecting the valve steam to the bell or sound producing element.

My device has a tubular body portion 4 formed with a threaded nipple 5 adapted to be secured in a suitable fitting or tapped hole in a compressed air line or in any other source of fluid under pressure. This body portion has a nut 6 integral therewith to facilitate securing the device to the support. An end 7 of the body 4 is adapted to communicate with the source of fluid and is formed with a conical seat for a closure 8. This closure is secured to a valve stem 9, which extends axially through the tubular body 4 and projects into a coaxially disposed sound producing element or bell 10. The bell 10 has a sleeve portion which slidably fits the body 4 and encloses a coiled spring 11 for normally holding the valve in closed position. One end of the spring 11 rests on an internal shoulder in the body 4 and its other end abuts against a head 12 which has an axial opening to receive an end of the stem 9. A transverse bore in the bell 10, head 12 and stem 9 is provided for a connecting pin 13 fitting snugly within said bore. A passage 14 through the head 12 is formed by cutting away the periphery of said head in such position as to direct compressed air or other fluid against an edge or lip 15 formed at one side of an oblique slot in the bell 10 constituting the outlet mouth for fluid.

The spring 11 is held under compression between the head 12 and shoulder in the

body 4 so that, in order to operate the whistle, the bell 10 is actuated to compress the spring and remove the closure 8 from its seat in the body 4. The stem 9 is spaced from the body 4 and bell 10 to allow the free flow of the fluid under compression to the passage 14 when the valve is opened.

My device is constructed from a small number of rugged parts and is rendered unusually durable by my arrangement of the short valve stem 9 connected to the lower portion of the bell which is guided by its smooth, cylindrical bearing on the body 4, said bearing being of ample length to prevent accidental bending of the body portion and bell out of alignment. It will be further noted that the head 12 performs the double function of connecting the valve stem with the sound producing bell and directing the blast of air against the lip 15 of the bell. The bell may also be employed as an actuating member which is manipulated to open the valve and may be constructed from a short section of standard pipe, preferably closed at one end.

Having described my invention what I claim as new and desire to protect by Letters Patent is:

1. A whistle having in combination a hollow body adapted to be placed in communication with a source of fluid under pressure, a bell slidably engaging said body along a telescoping portion of the same, said bell being formed with a sound producing lip, a valve closure having a seat in said body and means for operatively connecting said bell and closure and for normally retaining said closure on its seat comprising a valve stem and a coiled spring confined on said stem within the telescoping portions of said bell and body.

2. A whistle having in combination a hollow body adapted to be placed in communication with a source of fluid under pressure and formed with a valve seat, a valve closure adapted to engage said seat, a valve stem with in said body and connected to said closure, a sound producing element mounted in continuation of said body and having an interior opening in communication with the interior of said body, a head on said stem engaging

the interior of said element, a spring confined within said body and element and arranged to engage said head to normally retain said closure in engagement with said seat, a lip formed on said element and a passage formed in said head to direct fluid against said lip.

3. A whistle having in combination a tubular body adapted to be secured to a support, said body having an end opening adapted to be placed in communication with a source of fluid under pressure and being formed with a valve seat adjacent to said opening, a bell closed at one end and having a sleeve portion at its other end slidably engaging said body, a valve closure arranged to engage said seat, a valve stem extending longitudinally in said body and sleeve portion and connected to said closure at one end, a head on the other end of said valve stem, means rigidly connecting said head and stem to said bell, a spring confined within said sleeve portion and body and engaging said head to normally hold said valve in closed position, said bell being formed with an outlet opening for fluid located in the side of said bell between said head and closed end and passages for fluid in said body, sleeve portion and head for directing fluid to said outlet opening.

30 In testimony whereof, I have hereunto signed my name to this specification.

ALBIN W. GRONQUIST.
